FIG. 2.

INVENTOR

Ethel Eaton Stricker

UNITED STATES PATENT OFFICE

109,347

DESIGN FOR A NEGLIGEE

Ethel Eaton Stricker, New York, N. Y.

Application January 27, 1938, Serial No. 74,576

Term of patent 3½ years

To all whom it may concern:

Be it known that I, Ethel Eaton Stricker, a citizen of the United States of America, residing in New York city, in the Borough of Manhattan, county and State of New York, have invented a new, original, and ornamental Design for a Negligee, of which the following is a specification, reference being had to the accompanying drawing, forming part thereof, wherein,

Figure 1 is a front view of a negligee showing my new design.

Figure 2 is a rear view of the negligee shown in Figure 1.

The characteristic feature of my design resides in the specific multi-colored bands superimposed upon the specific negligee around the neck, on the bow at the waistline, and around the bottom, as shown.

I claim:

The ornamental design for a negligee, substantially as shown and described.

ETHEL EATON STRICKER.
